FURNACE TUYÈRE

Clifford E. Harrison, Philadelphia, Pa., assignor
to American Engineering Company, Philadelphia, Pa., a corporation of Pennsylvania

Application June 10, 1932, Serial No. 616,434

3 Claims. (Cl. 110—44)

This invention relates to stoker fired furnaces, and more particularly to the tuyères employed in such devices.

The tuyères employed in stoker furnaces, as is well known in the art, constitute the fuel supporting grates and are so constructed that draft air may pass therethrough from a pressure chamber to the fuel bed. These tuyères obviously are subjected to extremely high temperatures, especially when preheated draft air is employed. During operation of stokers of the underfeed type, while many of the tuyères may be protected to a certain extent by a layer of green fuel or fuel which has not yet reached the incandescent stage, it often happens that a thin fire develops in certain portions of the fuel bed with the result that incandescent fuel comes into direct contact with the tuyères. The tuyères subjected to such conditions may become damaged to such an extent that replacement thereof by new ones is necessary. It has been found that in most instances the nose portion is substantially the only part of the tuyère that is damaged; nevertheless in the older constructions the entire tuyère must be removed and replaced with a new one.

It is an object of the present invention to construct a tuyère block having two or more removable parts so that in case one of these parts should become damaged it is only necessary to replace that part and not the entire tuyère block.

A further object is to provide a tuyère block having a body portion and a nose portion removably attached thereto, said portions being so connected that but little heat is conducted to said body portion through said nose portion.

A more specific object of the invention is to provide a sectional tuyère block having interlocking means between the sections thereof which effectively secures them intact and yet permits ready replacement of any of the sections should it become damaged.

A further object is to provide a tuyère block having a series of substantially hollow air cooled projections which define passages through which draft air may pass.

A further object is to provide a sectional tuyère block having novel means provided thereon for distributing the draft air to all portions thereof.

A still further object of the present invention is to provide a tuyère block having means thereon defining passages through which air may pass which are so constructed and arranged that

clogging of the passages during operation of the stoker is prevented.

Other and further objects will become apparent as the description of the invention progresses.

Of the drawings:

Fig. 1 is a side elevational view taken through one of the retorts of a multiple retort underfeed stoker, showing the arrangement of the tuyère blocks, extension grates, and the fuel feeding elements.

Fig. 2 is a plan view of one of the tuyère blocks comprising the present invention.

Fig. 3 is a side view of the tuyère block shown in Fig. 2.

Fig. 4 is a sectional view taken on line 4—4 of Fig. 2.

Fig. 5 is a view taken on line 5—5 of Fig. 2.

Fig. 6 is a plan view of a modified form of tuyère block.

Fig. 7 is a side view of the tuyère block shown in Fig. 6.

Fig. 8 is a sectional view taken on line 8—8 of Fig. 6.

Fig. 9 is a view taken on line 9—9 of Fig. 6.

Fig. 10 is a perspective view of the tuyère blocks shown in Figs. 2 to 5 inclusive, in inverted position, and

Fig. 11 is a perspective view of the tuyère blocks shown in Figs. 6 to 9 inclusive, in inverted position.

Referring to the drawings, the numeral 1 indicates the front wall of a furnace equipped with a multiple retort underfeed stoker 2, having alternately disposed retorts 3 and tuyère rows 4 extending lengthwise of the stoker and inclining downwardly from front to rear thereof. Fuel is supplied to the stoker from hoppers 5 which communicate with cylinders 6, each having a fuel feeding ram 7 provided therein. A series of pushers 8 are provided in the bottom of each retort 3 for underfeeding the fuel along said retorts. Extension grates 9 provided at the rear of the stoker feed the residue into an ash pit 10.

The fuel feeding rams are actuated by any suitable power mechanism indicated at 11 and at each reciprocation thereof predetermined quantities of fuel entering the cylinders 6 from hoppers 5 are fed to the retorts 3. The pushers and extension grates are also actuated by the power mechanism 11 through the connections indicated generally as 12. Inasmuch as the specific construction of the operating mechanism for the rams, pushers and extension grates forms no part of the present invention, a detailed description thereof is unnecessary.

The tuyère blocks 4 are supported upon the upper edges of the walls 13 of adjacent retorts and span the space therebetween, as shown in Fig. 1. The chamber beneath the tuyère blocks defined by adjacent walls 13 communicates with a pressure chamber 14 common to the series of tuyères and into which draft air is supplied by any suitable blower apparatus (not shown).

For the purpose of illustration but one retort 3 and row of tuyère blocks 4 is shown, it being obvious that any number may be employed.

The terms "front" and "rear" hereinafter employed in the description of the various elements comprising the present invention, it is to be understood, indicate those portions of the elements disposed towards the front and rear respectively of the furnace.

Referring to Figs. 2 to 5, it is seen that each tuyère block 4 comprises a substantially rectangular body portion 16 and a substantially triangular nose portion 17. The body portion 16 of each tuyère block comprises a relatively thin flat portion 18 which is defined by side edges 19 and 20 and front and rear edges 22 and 21, respectively. The side edges 19 and 20 terminate near the rearwardly disposed end thereof in converging portions 23 and 24 which extend to the rear edge 21. The front end of body portion 16 is provided with a reduced portion 25, having side edges 26 and 27, which, when the tuyère blocks are assembled in the stoker, lie in close juxtaposition to the inner surfaces of side plates 13. Depending from the lower surface of portion 18 are a pair of elongated projections 28 and 29 having substantially flat lower surfaces 30 and 31, which in assembly rest upon the upper surface of the next lower tuyère block of the series. Projections 28 and 29 are also provided with inclined surfaces 32 and 33, the inclination of which corresponds with that of side plates 13, and which when the tuyère blocks are assembled in the stoker, rest upon the upper edges of said side plates 13. Also depending from the lower surface of body portion 16 is a stud 34 which engages into an aperture 35 of the next lower tuyère block of the series when the tuyères are assembled on the stoker. It will be noted that projections 34 and apertures 35 are in longitudinal alignment and are positioned substantially midway between side edges 19 and 20 of the tuyère block. A substantially U shaped slot 36 is provided at the rearwardly disposed end of portion 16 midway between the converging portions 23 and 24. The walls of slot 36 converge as shown in Fig. 2, into a rounded neck portion 37 near the rear edge 21 of body portion 16. This slot receives a correspondingly shaped locking lug 38 extending forwardly of nose portion 17. The rear edge 21 of body portion 16 is also provided with an extension 39 with which an extension 40 provided along the forward edge 41 of nose portion 17 overlaps.

Nose portion 17 also comprises a relatively thin portion 42 having side edges 43 and 44 which converge, as shown in Fig. 2, and lie in substantially the same vertical plane as the converging edges 23 and 24, respectively, of body portion 16. Side edges 43 and 44 terminate in a substantially arcuate portion 45. The upper surface of nose portion 17 is substantially flat and in assembly lies in the same horizontal plane as the upper surface of portion 16, as shown in Figs. 2 to 5. Depending from the lower surface of nose portion 17 is a series of projections 46, 47, and 48, which

define passages 49 and 50 through which draft air may pass. The forwardly disposed sides 51 and 52 of projections 47 and 48 also form, with the rounded rearwardly disposed ends 53 and 54, respectively, of projections 19 and 20, passages 55 and 56 through which draft air may also pass. The sides 60 and 61 of projection 46, and the arcuate portion 62 thereof, terminate inwardly of the outer edges of nose portion 17, and incline downwardly and inwardly as shown in Figs. 3 to 10. Projection 46 is formed with a flat base 63 which rests upon the next lower tuyère block of the series when the tuyère blocks are assembled on the stoker.

As shown more particularly in Figs. 2 and 4, an aperture 66 is provided in nose portion 17 near the rearwardly disposed end thereof through which some of the air entering the interior of projection 46 is discharged to the fuel bed.

The outer sides 67 and 69 of projections 47 and 48, respectively, also terminate inwardly of side edges 43 and 44 of nose portion 17, and incline downwardly and inwardly therefrom. These projections are also provided with base portions 68 and 70, respectively, which rest upon the upper surface of the next lower tuyère block of the series when the tuyère blocks are assembled on the stoker. By constructing projections 46, 47 and 48 in this manner, substantially the entire lower surface of each nose portion 17 is cooled by the incoming draft air. The heat transfer between the nose portions of adjacent tuyère blocks is also relatively small owing to the reduced areas of the base portions of said projections.

It is also seen, that by this construction clogging of the passages by slag or other formations which occur during furnace operation is prevented. The inclined sides of each projection, which are set back from the outer edges of the tuyère block, form in effect channels around the outer surfaces thereof which permit air to flow therethrough in case an obstruction is encountered adjacent one of the passages.

In order to assemble each tuyère block it is only necessary to bring the locking lug 38 into registering position with slot 36 and to then lower the nose portion 17 until the overlapping extensions 39 and 40 are brought into engagement.

It will be noted that the forwardly disposed side 57 of each locking lug 38 extends downwardly a considerable distance below the lower surfaces of portions 18 and 42 of the tuyère block, and that the lower edges 58 of the sides thereof incline upwardly and rearwardly as shown in Figs. 3 and 4. By this construction the sections 16 and 17 of each tuyère block 4 are effectively locked, and will remain intact even in case the parts thereof become distorted during operation of the furnace.

When the tuyère blocks are assembled on the stoker, the portions 16 and 17 thereof are secured against relative vertical movement by the overlapping arrangement of the superimposed tuyère blocks. The weight of the fuel supported by the tuyère blocks also has a tendency to maintain the parts in locked relation.

The modified tuyère blocks 4' shown in Figs. 6 to 9 are similar in general construction to the tuyère blocks 4 just described. These tuyère blocks also comprise a substantially rectangular body portion 16' and a substantially triangular nose portion 17', the former also having a substantially U shaped slot 36' which receives the correspondingly shaped locking lug 38' extending

ing forwardly from the latter. Each tuyère block 4' is also provided with depending projections 19' and 20', and a locking lug 34' which engages in a substantially circular aperture 35' of the 5 next lower tuyère block of the series. Extending rearwardly from locking lug 34' are a pair of spaced ribs 71' and 72' which extend substantially to the rear edge 21' of portion 16'. The lower edges 73' and 74' of ribs 71' and 72', 10 respectively, lie in a plane slightly above the plane in which the lower surfaces 30' and 31' of projections 28' and 29' lie so that air may enter the chamber defined by said ribs. A pair of spaced ribs 75' and 76' are also provided on 15 the lower surface of nose portion 17' and extend substantially the entire length thereof. These ribs are in alignment with ribs 71' and 72', respectively, and the lower edges 77' and 78' thereof lie in substantially the same horizontal plane 20 as the lower edges 73' and 74' of ribs 71' and 72', respectively. The lower edges 79' and 80' of the rearwardly disposed portion of ribs 75' and 76' extend downwardly from edges 77' and 78', and in assembly rest upon the upper surface of the 25 next lower tuyère block of the series. An aperture 81' is provided at the rearwardly disposed end of nose portion 17' so that the air entering the chamber defined by the ribs just described may be discharged into the fuel bed.

30 Spaced from ribs 75' and 76' are a pair of substantially triangular shaped ribs 82' and 83' which extend inwardly from side edges 43' and 44', respectively, of nose portion 17'. The forwardly disposed sides 84' and 85' of projections 82' and 83' are curved and form with the rounded forward ends 53' and 54' of projections 19' and 20', passages 86' and 87' through which draft air may pass.

The sides 88' and 89' of ribs 82' and 83' and 40 the outer sides 90' and 91' of ribs 75' and 76' incline outwardly and inwardly, respectively, as shown in Fig. 9, thus forming triangular shaped passages 92' and 93' through which the draft air passes. The lower surfaces of ribs 82' and 45 83' lie in the same horizontal plane as the lower edges of ribs 75' and 76' and projections 19' and 20', and in assembly also rest upon the upper surface of the next lower tuyère of the series.

From the foregoing description, it is seen that 50 draft air flowing through the tuyères comes into contact with substantially the entire lower surface thereof. The body portion 16 of each tuyère block is not only effectively cooled by the incoming draft air but is somewhat removed from the 55 burning fuel so that but little damage occurs thereto during operation of the furnace. The nose portions 17 of the tuyère blocks, however, are subjected to higher temperatures and under certain conditions may become damaged from 60 time to time and require replacement by new ones. This portion of the tuyère block, however, constitutes but a small part of the entire tuyère block and thus the cost of maintenance is very small. It is also seen that but little of the heat 65 absorbed by nose portion 17 is conducted to body portion 16 because of the joint therebetween and thus damage to the latter is further prevented. By the novel interlocking means between the nose and body portions of the tuyère block, bolt, 70 rivet, key, or other troublesome forms of fastening means are entirely dispensed with, and replacement of damaged parts may be readily made.

The illustrated embodiments show tuyère 75 blocks made up of but two parts. It is obvious,

however, that further divisions may be made, and also that the interlocking connections between the parts may be reversed if it is deemed desirable, without departing from the present invention. It therefore is to be understood that 5 the present invention is not to be limited to the specific constructions shown herein but only by the scope of the claims which follow.

What is claimed is:

1. A furnace tuyère block, adapted to comprise one of a series arranged in superimposed stepped relation, said tuyère block having a relatively flat body portion, and a series of projections provided thereon defining passages through which air may pass, said projections each having 10 a side, end, and a bottom wall forming an open chamber into which air may enter, and the side walls of said projections inclining downwardly and inwardly, forming reduced bottom wall surfaces. 20

2. A nose piece adapted for assembly with the body portion of a furnace tuyère block adapted to comprise one of a series arranged in stepped relation, said nose piece having a substantially smooth upper surface and a series of projections 25 provided on the under surface thereof defining passages for draft air, each of said projections having a side, end, and a bottom wall forming an open chamber into which air may enter, and the side walls of said projections inclining inwardly 30 from the corresponding edges of said nose piece forming reduced base portions adapted to contact the next lower tuyère block of the series.

3. A nose piece adapted for assembly with the body portion of a furnace tuyère block, adapted to comprise one of a series arranged in stepped relation, said nose piece having a substantially smooth upper surface, a plurality of projections depending from the under side of said nose piece defining passages for draft air, certain of said 40 projections extending longitudinally of the nose piece in spaced relation forming an air chamber, an outlet opening provided at the forward end of said chamber, and a locking lug for securing said nose piece in position projecting from 45 one edge thereof. 35

4. A tuyère block comprising a substantially rectangular body portion adapted for assembly with a nose portion, said body portion having a flange provided along one edge thereof, means 50 provided adjacent said edge adapted to interlock with the securing means provided on an associated nose portion, a pair of ribs depending from the under side of said body portion and extending longitudinally thereof in spaced relation forming an air chamber, and additional means depending from the under side of said body portion for supporting the same, and forming with said ribs first named, passages for draft air. 55

5. A furnace tuyère block adapted to comprise one of a series arranged in superimposed stepped relation, said tuyère block comprising a body portion, and a nose portion removably secured thereto, a series of projections provided on the under side of said nose portion defining passages for draft air, each of said projections having a side, end, and a bottom wall forming an open chamber into which air may enter, the side walls of said projections inclining inwardly from the corresponding edges of said nose piece forming reduced base portions adapted to contact the next lower tuyère block of the series. 70

6. A furnace tuyère block, comprising a substantially flat body portion having a locking slot 75 provided at the rearwardly disposed end thereof, 75

and a nose portion extending rearwardly of said body portion, means for securing said nose portion to said body portion forming in assembly a self contained tuyère unit, said securing means comprising a lug extending forwardly from said nose portion which engages in said slot provided in the rearwardly disposed end of said body portion, and the vertical dimension of at least a portion of said lug being greater than that of the body portion bounding said slot whereby disengagement of said nose portion from said body portion may be effected only by relative vertical movement of said parts.

7. A furnace tuyère block comprising a substantially flat body portion, and a substantially flat nose portion removably secured thereto, said nose portion extending rearwardly of said body portion and forming therewith a self contained unit, means for attaching said nose and body portions comprising a lug extending from one of said portions which engages into a slot provided

in the other of said portions, the upper surfaces of said lug, and nose and body portions lying substantially in the same plane thereby providing a substantially smooth continuous surface, and means provided on at least one of said portions defining passages for draft air.

8. A furnace tuyère block adapted to comprise one of a series arranged in stepped relation, said tuyère block comprising a substantially flat body portion, and a nose portion arranged in abutting relation therewith and extending rearwardly thereof, overlapping means provided on said body and nose portions forming a seal along the abutting edges thereof, and means for attaching said nose and body portions comprising a locking lug extending from one of said portions which engages into a slot provided in the other of said portions, and means provided on the under side of said nose portion defining passages for draft air.

CLIFFORD E. HARRISON.
